PACKAGE AND CLOSURE

William P. White, Glencoe, Ill., assignor to White Cap Company, Chicago, Ill., a corporation of Delaware

Application July 24, 1941, Serial No. 403,844

3 Claims. (Cl. 215—40)

1

This invention relates to packages of a sort suitable for the preservative packaging of food-stuffs and the like and wherein a receptacle in the nature of a glass tumbler or jar is closed and hermetically sealed by a closure cap which is retained in place by atmospheric pressure.

One of the objects of this invention is the provision of such a package which may be supplied to the packer at very low cost because of the facts that the glass receptacle may be made quite thin and the closure is of a simple construction which permits its being manufactured at very low cost.

Another object is the provision of such a package wherein the receptacle and closure are so formed and related that the closure may be applied and sealed on the receptacle very quickly and with reliable certainty incident to high-speed commercial packing procedure.

Another object is the provision of such a package in which the closure will remain securely in place when sealed on the receptacle and form a buffer or fender for protection of the glass receptacle against lateral impacts, yet which may be removed quickly and easily by the housewife when desired, without involving any puncturing or mutilation of the closure itself and without subjecting the fragile thin glass container to dangerous stresses or pressures.

Another object is the provision of a package of the sort specified above and in which the form and proportions of the closure and the receptacle are such that the closure will receive the mouth of the receptacle very freely, so that it may drop onto it quite quickly and readily into the position for sealing, and yet wherein the extent of eccentricity of the closure on the receptacle is limited in such fashion as to prevent a disproportionate or excessive overhang or lateral projection of the closure at one side of the receptacle as compared with the extent of overhang or lateral projection at the diametrically opposite side.

Other objects and advantages of the invention will be pointed out or indicated hereinafter or will be apparent to one skilled in the art upon an understanding of the invention or its employment in use.

For the purpose of aiding in explanation of the invention, I show in the accompanying drawing forming a part of this specification, and herein-after described, one form in which it may be embodied. It is to be understood, however, that this is presented merely for the purpose of illustration and hence is not to be construed in any fashion for the purpose of limiting the appended

2

claims short of the true and most comprehensive scope of the invention in the art.

In said drawing:

Fig. 1 is a fragmentary view of the upper portion of a package embodying my invention, showing the upper portion of the receptacle in elevation and the closure in section and in process of being applied to the receptacle; the parts are shown on an enlarged scale and parts are broken out of both the receptacle and the closure in order to reduce the lateral extent of the figure, consequently, the width of the figure as here illustrated is in a very considerably reduced proportion relative to the thickness and height of the parts;

Fig. 2 is a similar illustration showing the relationship of the upper end portion of the receptacle and the closure when the latter has dropped to rest thereon, as from the relationship shown in Fig. 1, all of the parts being shown in section;

Fig. 3 is an illustration similar to Fig. 2 but showing the relationship of the parts after the closure has been pressed to sealing position on the receptacle;

Fig. 4 is a detail in the nature of an elevational section through a lateral portion of the closure and the upper portion of an associated receptacle, the parts being shown on a scale considerably enlarged over that of the preceding figures; and

Fig. 5 is a detail illustrating the relationship of the closure to the receptacle in the course of the application of the closure by a procedure now quite generally used, the illustration showing a portion of the closure and upper portion of the receptacle in vertical section.

For the preservative packaging of food products in glass, the use of thin glass receptacles is desirable from the standpoint of customer appeal and saving in shipping weight and packaging bulk. Because of their greater frangibility, however, thin glass receptacles require that the packaging and sealing operations be performed with increased accuracy and with light pressures

and, moreover, increase the difficulty of obtaining airtight seals. The improvements constituting the present invention have been found effective to eliminate many of the serious difficulties and disadvantages which heretofore have attended the use of thin glass receptacles in commercial packing of commodities in vacuo. The nature of the invention can be most quickly ascertained by reference to the illustrative embodiment shown in the drawing.

The package constituting the present invention

tion comprises a glass receptacle, which is designated generally by the reference numeral 10, and a closure, which is designated generally by the reference numeral 11. The receptacle may be in the form of a jar, tumbler or the like and may be of the character of very thin pressed ware. It is formed with an outwardly projecting peripheral bead 12 at its upper end, whereby the thickness of the wall at or adjacent the top rim is considerably increased. The rim is formed with an annular crown 14, which throughout its annular extent lies as nearly as possible in a common plane approximately perpendicular to the axis of the receptacle. This crown is located an appreciable distance inwardly from the perimeter or outermost lateral surface of the bead 12.

The closure 11 comprises a shell which is formed from sheet material such as tin plate of suitable strength and stiffness, and it is shaped with a top portion 15 which is of somewhat greater diameter than the receptacle bead 12, and a skirt which depends from the periphery of the top 15 and is shaped adjacent the top with an outwardly projecting circumferential beading 16, and below said beading with an approximately cylindrical portion 17. The deflection of the skirt material from the bead 16 to the depending skirt portion 17 is quite abrupt, the bend at A being substantially sharper than, or on a shorter radius than, the concave curvature of the bead 16, as illustrated by way of example in Fig. 4. The cylindrical portion 17 is of somewhat smaller external diameter than the beading 16, and its internal diameter exceeds the outer diameter of the receptacle mouth bead 12 sufficiently to permit the latter to enter freely and readily within the shell skirt when the closure and receptacle mouth are in approximately coaxial or concentric relationship. A gasket 18 of flat ring form is adherently secured to the top 15 in approximately concentric relationship with the skirt. This gasket is formed of a sealing material which is fairly firm but plastic at ordinary room temperature and which may be rendered slightly tacky by heating. A suitable material is a rubber composition which has been cured in such fashion as to give it the desired plasticity and firmness. The thickness of the gasket approximates the height of the beading 16, and its external diameter is preferably approximately the same as the internal diameter of the cylindrical skirt portion 17, while its width considerably exceeds the radial thickness of the vessel wall inclusive of the bead 12. This gasket preferably is pre-formed and inserted into the shell through the skirt portion 17 and secured in place by pressing it against the top 15 while heat is applied to the latter in amount sufficient to render the contacting portion of the gasket slightly tacky and cause it to adhere to the under surface of the top. In this fashion the gasket may be intimately and firmly connected to the shell. The depth of the shell skirt is such that the cylindrical portion 17 will be opposite the widest diameter of the bead 12 and will extend somewhat below said bead when the under surface of the gasket 18 is resting on the crown 14. This relationship of the parts is illustrated in Fig. 2, and it will be seen that when so associated the receptacle bead 12 is adapted for cooperation with the skirt portion 17 to insure that the line of contact between the crown 14 and the gasket 18 is located a substantial distance inwardly from the periphery of the gasket at all points in the

circumferential direction. In Fig. 2 the parts are shown in the relationship wherein the skirt portion 17 is in contact with the bead 12 at one side of the package. This represents the position of maximum eccentricity of the closure relative to the receptacle, and it will be observed that in that relationship the skirt portion 17 below the point of contact with the bead is held spaced an appreciable distance outwardly from the receptacle wall, whereas at the opposite side of the package the margin of the skirt is, perforce, spaced from the receptacle wall by a slightly greater distance as illustrated in Figs. 2 and 3. Moreover, the shell skirt is sufficiently shallow to permit the closure to be swung freely upwardly to a position where the skirt is higher than the mouth rim at one side of the receptacle while the gasket remains in contact with the mouth rim at the diametrically opposite location.

The thickness of the gasket is such as to permit the crown of the mouth rim to be pressed into it a substantial distance without carrying the perimeter of the bead 12 upwardly beyond the skirt portion 17. Due to the fact that the crown is spaced a substantial distance inwardly from the outer margin of the gasket when the closure is resting loosely on the receptacle, the downward movement of the shell in the sealing operation causes displacement of the plastic gasket material in the outward radial direction from the entering crown of the receptacle as well as in the inward radial direction, and the continuing cooperation of the bead 12 with the skirt 17 during downward movement of the closure 11 prevents its creeping laterally on the receptacle to a position where the outer margin of the gasket would reach the crown. It is to be observed also that the beading 16 accommodates outward displacement of the plastic gasket material incident to the intrusion of the mouth rim. As a consequence of these several factors, a broad sealing area or area of contact between the mouth rim and the gasket material is obtained clear around the mouth of the receptacle, and the intrusion of the mouth rim into the gasket may be accomplished with comparatively light pressure. This latter effect, as well as the fact that the entry of the crown into the gasket is at a substantial distance from the periphery of the latter, are of particular importance when thin glass receptacles are used.

The application and the sealing of the closure upon the receptacle are preceded by the exhaustion or evacuation of air from within the closure and the head space of the receptacle, so that after the closure has been pressed to sealed position as explained above, the pressure within the sealed package will be below that of the atmosphere and the latter will hold the closure in place. The closure may be removed by prying it upwardly in the customary manner by means of a bottle opener of the conventional hook type.

As pointed out above, the cooperation of the bead 12 with the skirt portion 17 limits the extent to which the closure may be displaced eccentrically relative to the receptacle, and also holds the lower margin of the skirt spaced away from the periphery of the vessel at all points. The limiting of the eccentricity of the closure contributes to the appearance of the package. The spacing of the lower margin of the closure from the wall of the receptacle has several advantages. When so spaced, the lower portion of the closure skirt constitutes a buffer which will yield under lateral impacts without transmitting their force to

the glass receptacle locally. The projecting margin of the skirt affords secure engagement for the opener at any point around the package, and hence reduces the likelihood of the glass receptacle being broken by the slipping off of the opener. One of the most important advantages lies in the fact that the construction avoids the application of cramping or constrictive crushing stresses to the thin glass receptacle by the prying leverage of the opener in the closure removing operation. Particularly in the case of packages which, after sealing, have been subjected to cooking or heat sterilization, the bond between the gasket and the rim of the receptacle may be very strong, due to the vulcanizing of the gasket material to the glass. Deep intrusion of the receptacle mouth rim into the gasket also contributes to the tenaciousness of the bond. Under such circumstances, the bond may be so strong that the lower portion of the closure skirt will be drawn quite considerably out of its circular form by the prying force of the opener, before the bond is broken. In the use of closure caps of prior constructions on thin glass receptacles it has been found that this distortion of the shell skirt has been sufficient in some instances to cause the breaking of the thin receptacle. By the present construction, such breakage is effectively prevented. The form and relationship of the bead 12 on the receptacle and the skirt portion 17 of the closure shell are such that the skirt 17 is spaced a substantial distance away from the wall of the receptacle when the closure is in sealed position on the receptacle, even though the closure is at a position of maximum eccentricity relative to the receptacle illustrated in Fig. 3. Thus there is provided between the skirt portion 17 and the wall of the receptacle a clearance which, at its minimum, is as wide as the bead 12 is thick radially, which clearance allows for maximum inward deflection of the skirt margin under the opening pressure. Furthermore, the bead 12 itself interposes a limiting effect upon the inward deflection of the skirt, as when the skirt comes into engagement with it the inwardly deflectable portion of the skirt is shortened to that part which is below the point of contact with the bead. As a consequence, the depending skirt of the shell is not permitted to reach the wall surface of the receptacle and exert crushing stresses upon it before the closure is freed from the receptacle by the lifting force from the opener. Thus the thin glass vessel is safeguarded against fracture from that sort of an occurrence in the opening of the package.

The peripheral skirt beading 16, in addition to affording space for lateral displacement of the gasket material as above mentioned, affords an important fender or protection for the glass vessel against impacts such as might result from lateral impingement of one package against another or the falling over of a package on a conveyor or the like. Moreover, the beading 16 has a definite stiffening and shape-maintaining effect upon both the top portion 15 and the skirt portion 17, as it resists the bending of the top portion 15 out of its normal plane and also resists the flexing of the skirt portion 17 out of its normal circular contour by prying pressure such as is customarily applied to those parts by an opener in the operation of lifting the closure from the receptacle to break the hermetic seal.

The construction affords additional advantages in the operation of applying the closure to the receptacle. For example, if the closure is applied

by hand or by being dropped straight downwardly onto the receptacle, the form of parts facilitates the entry of the receptacle mouth into the closure even though they are considerably out of alignment. Fig. 1 serves to show how the bead 12 will serve to guide the closure onto the mouth of the receptacle, even though the margin of the skirt may not be clear of the bead 12 at all points. This is of distinct advantage in facilitating the application of the closures while the receptacles are in progressive movement. Fig. 5 serves to illustrate the cooperation of the parts incident to the application of the closure in an apparatus of the sort illustrated in my U. S. Patent No. 1,920,539. The closures are fed in a series down an inclined chute marked C while the receptacles are moved progressively in a series in such fashion that the successive receptacles meet the successive closures at the lower end 20 of the chute and withdraw them therefrom incident to the further progressive movement of the receptacles. In such an operation it is necessary to have a suitable engagement of the closure by the upper portion of the receptacle to insure that the closure will be positively withdrawn from the chute, but at the same time it is important to hold the gasket entirely out of contact with the receptacle until the closure reaches an approximately horizontal position over the receptacle. In Fig. 5 it is seen how the bead 12 overhangs the lower portion of the skirt at the point of contact and thereby effects a very secure engagement which will insure that the closure is positively withdrawn from the chute, even though the point of engagement between the bead and the closure skirt is adjacent the lower margin of the latter so that the gasket 18 is spaced a substantial distance above the mouth rim of the receptacle.

Accordingly, it is to be observed that by virtue of the cooperative character and arrangement of the parts, my improved package greatly facilitates the packing and sealing operations, affords important safeguards against injury, increases the security and reliability of the airtight seal, facilitates its opening, and safeguards the frangible receptacle against breakage incident to the application of upward prying pressure to the closure skirt for the purpose of removing the closure.

What I claim is:

1. In a vacuum seal package comprising a frangible receptacle having an annular wall portion with an annular mouth rim having a peripheral bead encompassing it and projecting outwardly from the mouth rim and wall portion, a closure adapted for retention on the receptacle by atmospheric pressure alone, said closure comprising a shell having a top portion for covering the receptacle mouth and an annular skirt depending from said top portion, a gasket of plastic sealing material secured to the underside of the top portion and adapted to form a seal upon the annular mouth rim of the receptacle, the upper portion of said skirt being formed as a circumferential beading extending outwardly beyond the portion of the skirt therebelow, the portion of the skirt which is below said beading being deflected abruptly therefrom and being of approximately cylindrical form and of circumferential size and depth to swing freely clear of the mouth rim on one side of the receptacle while the gasket is in contact with the mouth rim on the opposite side, the depth of the skirt beading and thickness of the gasket being such that when the gasket is resting on the mouth rim of the receptacle in

position for sealing thereon, the bead of the latter will be within said lower portion of the skirt in position to space the skirt entirely away from the annular wall portion of the receptacle below the bead when the closure is moved downwardly 5 to sealed position on the receptacle.

2. In a vacuum seal package which includes a frangible receptacle having an annular mouth rim and an annular wall portion therebelow and an annular peripheral bead projecting outwardly 10 from said wall portion adjacent the rim, a closure adapted for retention on the receptacle by atmospheric pressure alone, said closure comprising a shell having a top portion for covering the receptacle mouth and an annular skirt 15 depending from said top portion, a gasket of plastic sealing material secured to the underside of the top portion adjacent the skirt and of size to form an air-tight seal upon the annular mouth rim of the receptacle, the upper portion of the 20 skirt for a depth approximating the thickness of the gasket being formed as a circumferential stiffening beading extending outwardly beyond the portion of the skirt therebelow, the portion of the skirt below the beading being of circumferential size and depth to admit entry of the mouth rim freely into contact with the gasket when the closure top is in canted relationship to the receptacle, said lower portion of the skirt depending approximately perpendicularly from the 25 plane of the top portion for cooperation with the periphery of the receptacle bead to insure a predetermined minimum radial clearance between the skirt and the wall of the receptacle below the

bead when the closure is moved downwardly to sealed position on the mouth rim.

3. A vacuum seal package comprising a receptacle having an annular wall portion with an annular mouth rim and an annular peripheral bead encompassing the mouth rim and projecting outwardly from said wall portion, and a closure adapted for retention on the receptacle by atmospheric pressure alone, said closure comprising a shell having a top portion for covering the receptacle mouth and a depending annular skirt, a gasket of plastic sealing material secured to the underside of the top portion and disposed to form an air-tight seal upon the annular mouth rim, the upper portion of the skirt being formed as an outwardly projecting annular beading and the lower portion of the skirt being of approximately cylindrical form and being of circumferential size and depth to be swung freely into and out of encompassing relationship with the bead on one side of the receptacle while the gasket is in contact with the mouth rim at the diametrically opposite location, the thickness of the gasket being such that when it is resting on the mouth rim of the receptacle preliminary to sealing, the peripheral bead of the latter will be within said lower portion of the skirt, said peripheral bead being of sufficient width in the radial direction to keep the skirt entirely spaced away from all portions of the receptacle wall below the perimeter of said bead when the closure is in sealing engagement with the receptacle.

WILLIAM P. WHITE.
